TRAPPER'S GLOVE

Filed July 2, 1929

By
Lacey Lacey, Attorney.

UNITED STATES PATENT OFFICE

PAUL G. HEINRICH, OF EDEN, NEW YORK

TRAPPER'S GLOVE

Application filed July 2, 1929. Serial No. 375,434.

This invention relates to apparel and more particularly to a glove for use by trappers and others whose work requires them to reach down quite far into water.

5 One object of the invention is to provide a glove formed of rubber so that it will be waterproof and having a hand covering portion and gauntlet or arm covering portion extending therefrom and of such length 10 that it will practically cover a person's arm to the shoulder and thereby allow the person wearing the gloves to reach deep into the water without getting wet.

Another object of the invention is to so 15 form the arm covering portion of the glove that it will be reinforced and prevented from slipping downwardly when worn, thereby eliminating danger of this arm covering portion slipping downwardly while 20 reaching into water and allowing the water to enter the glove through its open upper end.

Another object of the invention is to so 25 form the arm covering portion of the glove that its elbow portion will be extra strong and prevented from being liable to quickly wear out due to cracking of the rubber or extra wear which this portion is subjected to when the glove is worn.

30 Another object of the invention is to provide the arm covering portion with means causing it to be drawn tightly about the arm above the elbow and thereby preventing it from sliding downwardly.

35 The invention is illustrated in the accompanying drawing, wherein

Figure 1 is a perspective view of the improved glove.

Fig. 2 is a longitudinal sectional view 40 through the glove with the hand covering portion partly broken away.

Fig. 3 is a transverse sectional view taken on the line 3—3 of Fig. 2, and

Fig. 4 is a similar view taken on the line 45 4—4 of Fig. 2.

This improved glove consists of a hand covering portion 1 from which extends an arm covering portion or gauntlet 2. The hand covering portion is formed of soft rubber so that it will not interfere with easy

use of the hands but the rubber is sufficiently thick to prevent danger of its being easily torn or quickly worn through. The arm covering portion consists of a tubular sleeve or body 3 which is also formed of rubber 55 similar to the hand covering portion and merges into the hand covering portion at the wrist. A lining 4 formed of canvas or other suitable fabric is provided for the arm covering portion and adheres to the inner 60 face of this body. In fact, the lining or fabric sleeve 4 is first made and this sleeve is then coated with rubber in order to form the body portion. It will thus be seen that the lining or sleeve has intimate engagement 65 with the rubber body. Elastic bands 5 and 6 fit about the fabric lining, one close to the upper end of the glove and the other in such spaced relation thereto longitudinally of the glove that when the glove is worn 70 this second band 6 will be disposed above a person's elbow. Therefore, the two elastic bands will be disposed about a person's upper arm between the elbow and shoulder and the contraction of these bands will cause the 75 arm covering portion of the glove or gauntlet to be bound closely about the arm and prevented from slipping downwardly. Reinforcing ribs 7 are formed integral with the rubber body 3 and extend longitudinally 80 thereof between the wrist and upper end of the glove and these ribs are spaced from each other circumferentially of the arm covering portion so that they may brace the same and prevent it from crumpling while 85 at the same time not interfering with free bending of the arm at the elbows. There has also been provided a thickened portion 90 8 which corresponds in thickness to the ribs 7 and is of such length and width that the arm covering portion or gauntlet of the glove will be well reinforced at the elbow and prevent the glove from cracking or quickly wearing through when in use.

These gloves are intended for use by 95 trappers, hunters and others whose work requires them to reach downwardly into water of such depth that gloves of an ordinary length would not prevent a person's arms and the sleeves of a coat from becoming 100

ing wet. The hand covering portion is preferably of sufficient size to allow a pair of woolen gloves to be first put on and thereby afford warmth and the arm covering portion or gauntlet is of such length that it will practically cover a person's entire arm from the wrist to the shoulder. Therefore, a person wearing these gloves can reach deeply into water in order to find a muskrat or other animal which has dived into the water without getting his arms or coat sleeves wet. This will prevent a great deal of rheumatism and colds caused by a trapper getting his sleeves and arms wet when reaching into water. The elastic bands cause the upper portion of the gauntlet to be bound about the upper arms and the ribs 7 are sufficiently stiff to prevent the gauntlet portion from having a tendency to crumple and assist the elastic bands in retaining the gloves in proper position about a person's arms. It will thus be seen that I have provided a glove which, when worn, will serve very effectively to keep a person's hands and arms and the sleeves of a coat from becoming wet when reaching into water in order to recover a trapped animal or when doing any work which requires reaching into water.

Having thus described the invention, I claim:

1. A water-proof glove comprising a hand covering portion and an arm covering portion extending therefrom, the said hand covering being formed of rubber and the arm covering portion consisting of a rubber body merging into the hand covering portion, and ribs extending longitudinally upon the outer face of said body and spaced from each other circumferentially thereof, the elbow covering portion of the body being thickened to form a reinforcement of a thickness corresponding to the thickness of the ribs.

2. A water-proof glove comprising a hand covering portion and an arm covering portion extending therefrom, the said hand covering being formed of rubber and the arm covering portion consisting of a rubber body merging into the hand covering portion, a fabric lining adhering to the inner surface of said body, and elastic bands embedded in the body in encircling relation to the lining and spaced from each other longitudinally of the lining and adapted to draw the arm covering portion tightly about a person's arm and retain the glove in place.

3. A water-proof glove comprising a hand covering portion and an arm covering portion extending therefrom, the said hand covering portion being formed of rubber and the arm covering portion consisting of a rubber body merging into the hand covering portion, ribs extending longitudinally

upon the outer face of said body and spaced from each other circumferentially thereof, the elbow covering portion of the body being thickened to form a reinforcement of a thickness corresponding to the thickness 70 of the ribs, a fabric reinforcing lining adhering to the inner surface of said body, and elastic bands spaced from each other between the elbow reinforcement and upper end of the body and adapted to draw the 75 arm covering portion tightly about a person's arm and retain the glove in place.

In testimony whereof I affix my signature.
